Specification for Design.

Patented May 16, 1916.

Application filed July 19, 1915. Serial No. 40,802. Term of patent 7 years.

To all whom it may concern:

Be it known that I, ALFRED STONE, a citizen of the United States, residing at Oakland, in the county of Alameda and State of California, have invented a new, original, and ornamental Design for Lock-Casings, of which the following is a specification, reference being had to the accompanying drawing, forming part thereof.

Figure 1 is a view in end elevation of a lock constructed in accordance with my new design. Fig. 2 is a view in side elevation of

the same. Fig. 3 is a view in perspective, showing my new design.

I claim:

The ornamental design for a lock casing, as shown.

In testimony whereof I affix my signature in presence of two witnesses.

ALFRED STONE.
